OUTDOOR LIGHTING UNIT

Bjarne Netland, Liverpool, N.Y., assignor to Crouse-Hinds Company, Syracuse, N.Y., a corporation of New York

Filed Feb. 6, 1967, Ser. No. 5,692

Term of patent 7 years

(Cl. D48—31)

FIGURE 1 is a side elevational view of an outdoor lighting unit embodying my new and original design. The opposite side of the unit is a mirror image of the side shown.

FIGURE 2 is a bottom plan view.

FIGURE 3 is a top plan view.

FIGURE 4 is a rear end elevational view looking to the left in the above figures.

FIGURE 5 is a front end elevational view.

In FIGURES 1, 2, 3 and 4, the supporting pipe is shown in broken lines for illustrative purposes only.

I claim:

The ornamental design for an outdoor lighting unit, as shown and described.
